[57] CLAIM

The ornamental design for a compartmentalized lid for ice chest, as shown and described.

DESCRIPTION

FIG. 1 is a front elevational view of the compartmentalized lid for ice chest of the present design;

FIG. 2 is a back elevational view of the compartmentalized lid for ice chest of FIG. 1;

FIG. 3 is a left side elevational view of the compartmentalized lid for ice chest of FIG. 1;

FIG. 4 is a right side elevational view of the compartmentalized lid for ice chest of FIG. 1;

FIG. 5 is a top plan view of the compartmentalized lid for ice chest of FIG. 1;

FIG. 6 is a bottom plan view of the compartmentalized lid for ice chest of FIG. 1; and,

FIG. 7 is a top, front, right side perspective view of the compartmentalized lid for ice chest of FIG. 1 in an alternate position.

The broken lines showing an ice chest in FIG. 7 are for illustrative purposes only and form no part of the claimed design.
